US00D846644S

(12) **United States Design Patent** (10) **Patent No.:** **US D846,644 S**
Becker et al. (45) **Date of Patent:** **** Apr. 23, 2019**

(54) **SHEET WITH WRISTBAND**

(71) Applicant: **CCL Label, Inc.**, Framingham, MA (US)
(72) Inventors: **William Becker**, Rockport, NY (US); **Joseph Langan**, East Amherst, NY (US)

(73) Assignee: **CCL Label, Inc.**, Framingham, MA (US)

(**) Term: **15 Years**

(21) Appl. No.: **29/588,298**

(22) Filed: **Dec. 20, 2016**

(51) LOC (11) Cl. **20-03**

(52) U.S. Cl. **USPC D20/27**

(58) **Field of Classification Search**

USPC ..... D20/10, 11, 22-29, 35, 39, 40-43, 99; D14/485-495; D19/1 CPC G09F 1/00; G09F 1/02; G09F 2003/023; G09F 2003/0261; G09F 2003/0264; G09F 7/00; G09F 3/206; G09F 13/00; G09F 2007/1807; G09F 13/04; G09F 2013/0427; G09F 2013/0495; G09D 3/00

See application file for complete search history.

(57) **CLAIM**

The ornamental design for a sheet with a wristband, as shown and described.

DESCRIPTION

FIG. 1 is a front perspective view of a first embodiment of the design;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1; and,

FIG. 7 is a bottom view of the design of FIG. 1.

The broken lines illustrate portions of the article and form no part of the claimed design.

1 Claim, 3 Drawing Sheets
